COMBINED DISPLAY AND STORAGE CASE FOR A SAFETY RAZOR OR THE LIKE

Alan B. Lowry, Canton, Mass., assignor to The Gillette
Company, Gillette Park, Boston, Mass., a corporation of Delaware

Filed Aug. 16, 1965, Ser. No. 86,589

Term of patent 14 years

(Cl. D58—12.6)

FIG. 1

FIG. 5

FIG. 1 is a top plan view of a combined display and storage case for a safety razor or the like showing my new design, the broken line showing of the safety razor being for illustrative purposes only.

FIG. 2 is a view in front elevation.

FIG. 3 is a view in rear elevation.

FIG. 4 is an end elevational view as seen from the right of FIG. 1; and

FIG. 5 is a front perspective view of the lower portion thereof in a folded closed condition, the upper transparent lid having been removed.

I claim:

The ornamental design for a combined display and storage case for a safety razor or the like, substantially as shown and described.
